UNITED STATES PATENT OFFICE.

JOHN EDWIN PEDERSEN, OF HILLSBORO, ILLINOIS, ASSIGNOR TO AMERICAN ZINC, LEAD & SMELTING COMPANY, OF ST. LOUIS, MISSOURI, A CORPORATION OF MAINE.

MACHINE FOR CHARGING FURNACE RETORTS.

Application filed June 24, 1921. Serial No. 480,014.

To all whom it may concern:

Be it known that I, JOHN EDWIN PEDERSEN, a citizen of the United States, residing at Hillsboro, Montgomery County, Illinois, 5 have invented a new and useful Machine for Charging Furnace Retorts, of which the following is a specification.

This invention relates to machines for charging furnace retorts with ore.

10 An object of the invention is to provide an efficient machine for mechanically charging the retorts of ore furnaces.

Another object of the invention is to provide a machine of the character and for the 15 purpose mentioned, which is capable of adjustment and operation to fill or charge all of the retorts in the series.

Another object of the invention is to provide a machine for charging ore furnaces, 20 comprising mechanism for throwing the material into the retorts and improved means for delivering the material to said mechanism.

Another object of the invention is to provide 25 a novel and efficient mechanism for conveying the material to the machine.

In the drawings,

Fig. 1 is a side elevation of the machine 30 with parts of the hopper or chute in section and broken away.

Fig. 2 is an outer side or end elevation.

As shown, my invention comprises a car or truck 1, arranged to move upon the rails 2 of a track running parallel with the charging end of a furnace. The car or truck 1 supports a pair of rails 3, extending transversely of the truck 1, and having abutments 4 at their inner and outer ends. The frame of the machine comprising the 35 upright members 5 is operatively supported on the rails 3 by wheels 6. By this arrangement and construction, the entire machine, including the truck 1, may be moved along the track 2 to serve the different vertical tiers of retorts A; and the machine proper may be moved upon the track 3 transversely of the truck 1 toward and away from the ends of the retorts. The provision for outward movement of the machine proper on the track 3 is to permit the machine to be 45 adjusted to pass the fixed projecting portions of the furnace. Movement of the machine on the track 3 is stopped and limited to the abutments 4 which, as shown, may comprise up-turned ends of the rails. The

machine may be moved in either direction upon the track 3 by any appropriate device, as by a lever 7 pivoted to a bracket 8 on the machine frame and having a connection 9 with a stationary part of the track or support, whereby proper operation of the lever will move the machine toward or away from the ends of the retorts. The lever 7 is preferably equipped with a latch device 10 for engagement with the bracket 8 in the obvious manner shown in order to hold the machine rigidly in any of its different adjusted positions.

The frame of the machine which, as stated, comprises the upright member 5 supports and guides for vertical movement a frame 11. The shaft of a motor 12 mounted on the vertically adjustable frame 11 is belted to a pulley 13, attached to a shaft 14 in said frame 11. One or more balance 70 wheels 15 are attached to the shaft 14. A link 16 for each of the balance wheels 15 has one end pivoted thereto, eccentrically of the axis of the wheel, and the opposite end of said lever or levers being pivoted to the 75 upper end or ends of a lever or levers 17. The levers 17 are pivotally supported intermediate of their ends upon supports 18. The lower ends of each of the levers 17 have sliding pivotal connection 19 with a shovel 80 or thrower 20. The shovels or throwers 20 are operatively supported upon appropriate tracks carried by the adjustable frame 11, and in the form shown, comprising channel bars 21, adjustably supported upon a shaft 90 22 in the vertically adjustable frame 11. The shovels or throwers 20 have arms 23 extending at the sides of the tracks 21 and provided with rollers operating within the channels of said tracks.

From the foregoing it is apparent that the motor 12 rotates the shaft 14 having the balance wheels 15 attached thereto; and that the connections from said balance wheels oscillate the levers 17 with the result that the shovels or throwers 20 are operated on the tracks 21 toward and away from the charging ends of the retorts A. Moreover, the movement of said shovels or throwers toward the charging ends of the retorts is 100 very rapid, the momentum being sufficient to throw the material from the shovels or throwers to the inner ends of the retorts when the shovels or throwers are suddenly stopped near the ends of the retorts (Fig. 1). 110

As stated the tracks 21 are adjustable. In the specific form of the invention shown, the tracks 21 are pivotally supported and are capable of adjustment to different angles of inclination whereby said tracks may be made to support the shovels or throwers 20 to serve the retorts A, irrespective of the varying angles of inclination of the retorts. As shown, the outer ends of the tracks 21 are supported by an adjusting device, comprising a shaft 24 having threaded support in the frame 11 and having its lower end pivotally connected with the tracks 21, as shown in 25, Fig. 1. It is obvious that by turning the shaft 24 in proper direction the angle of inclination of the tracks 21 may be varied.

The material is delivered to the shovels or throwers 20 through a chute 26 provided for that purpose. The chute 26 is of telescopic construction, the upper section thereof being within a hopper 27 rigid in the main frame 5; and the lower section of the chute is supported by the vertically movable frame 11, so that the position of the frame 11 determines the length of the chute. When the frame 11 is raised within the main frame 5 the length of the chute is shortened by telescoping the sections of the chute 26 in the well-understood manner; and when the frame 11 is lowered in the main frame 5, the chute is lengthened. The result is that the discharge end of the chute is in the same position relative to the tracks 21 at all times. This provides for the proper discharge of the material into the shovels or throwers 20, irrespective of the positions of the retorts that are being served by said shovels or throwers.

The lower section of the chute 26 has a passage for each shovel or thrower 20 in the machine (Fig. 2). As stated in the specific embodiment of the invention shown, there are two shovels or throwers 20 so that the lower section of the chute is arranged to discharge material from two outlets, one for each of said shovel or throwers. A rotary valve device 28 is in each discharge outlet. The device 28 may be of any appropriate construction, and as shown, each of said devices comprises four vanes or wings extending radially from a rod or shaft 29. By turning the shaft or shafts 29, the discharge control devices 28 may be operated to discharge material from the chute 26. Provision is made for operating the discharge control devices 28 to discharge material from the chute when the shovels or throwers 20 are below the lower end of the chute. Each end of the shaft 29 pivotally supports a bifurcated lever 30. Each lever 30 supports a pawl 31 which is spring-pressed into engagement with a ratchet wheel 32, adjacently supported in rigid connection with the shaft 29. As the levers 30

are pivotally supported on the shaft 29, they may be moved in one direction without turning said shaft; but movement of said levers in the opposite direction causes the pawls 31 to turn the ratchet wheels 32 and thereby the shaft 29 to operate the discharge devices 28. The outer end of each shovel or thrower 20 has an upwardly extended part 33 which when the shovels or throwers are moved to position under the lower end of the chute 26, pass under the inner arms of the levers 30 and engage the lower arms of said levers 30, thereby actuating said levers to operate the discharge control devices 28 with the result that material is discharged from the chute into the shovels or throwers. The discharge devices are arranged to discharge only the desired amount of material at each operation. Inward movement of the shovels or throwers 20 engages the extended portions 33 thereof with the inner arms of the levers 30, thereby restoring said levers to the position shown in Fig. 1, the pawl 31 escaping from the peripheries of the ratchet wheels 32 delivering said movement. The inward movement of the shovels or throwers toward the ends of the retorts is very rapid and the momentum thereof is sufficient to throw material from the shovels or throwers to the inner ends of the retorts when the shovels or throwers are suddenly stopped near the ends of the retorts.

The frame 11 may be raised and lowered by winding or unwinding a chain or coupling 34, appropriately connected with the frame 11 and passing over sheaves or pulleys 35 to a winding drum 36.

Material may be conveyed into the hopper by an endless conveyor device 39 arranged to convey material from a car 38 and to discharge the material into the upper end of said hopper. The car 38 is connected and moved with the truck 1. The conveyor shown is of the endless belt type of familiar construction.

From the foregoing it will be seen that my invention satisfactorily and efficiently serves all of its intended purposes. The material is automatically discharged into the shovels or throwers as an incident of the operation thereof. The operation of the machine is comparatively rapid and the machine may be made to serve one or more vertical tiers of retorts simultaneously as desired.

I do not restrict myself to unessential features or limitations since it is apparent that the invention may be widely varied without departure from the nature or principle thereof.

What I claim and desire to secure by Letters Patent is:—

1. A machine of the character described, comprising a supporting frame located adjacent to the charging ends of retorts, movable

throwers carried by the frame for throwing material into the retorts, means for supporting the throwers at different heights necessary to throw material into retorts at different heights, and mechanism for moving the throwers rapidly toward the open ends of the retorts with sufficient momentum to throw the material to the inner ends of the retorts when the throwers are stopped near the ends of the retorts.

2. A machine of the character described, comprising a supporting frame located adjacent to the charging ends of retorts, movable throwers carried by the frame for throwing material into the retorts, means for supporting the throwers at different heights necessary to throw material into retorts at different heights, mechanism for moving the throwers rapidly toward the open ends of the retorts with sufficient momentum to throw the material to the inner ends of the retorts when the throwers are stopped near the ends of the retorts, and a track in said frame for supporting the throwers throughout their operation.

3. A machine of the character described, comprising a laterally movable frame located near the charging ends of retorts, a supporting truck for carrying the frame laterally to different adjacent positions, a thrower carried by said frame for movement toward and away from the charging ends of the retorts, means for supporting the thrower at different heights necessary to throw material into retorts at different heights, a chute for conducting material to load the thrower in any of the vertically adjusted positions of the thrower, and a mechanism for operating the thrower rapidly toward and stopping the thrower adjacent to the charging end of a retort, the momentum of the thrower being sufficient to throw the material therefrom to the inner end of the retort when the thrower is suddenly stopped.

4. A machine of the character described, comprising a laterally movable frame located near the charging ends of retorts, a supporting truck for carrying the frame laterally to different adjacent positions, a thrower carried by said frame for movement toward and away from the charging ends of the retorts, a chute for conducting material to load the thrower, mechanism for operating the thrower rapidly toward and stopping the thrower adjacent to the charging end of a retort, the momentum of the thrower being sufficient to throw the material therefrom to the inner end of the retort when the thrower is suddenly stopped, and means for supporting the thrower for operation at different angles of inclination.

5. A machine of the character described, comprising a frame supported near the charging ends of retorts, means for sup-

porting the frame in different vertical positions, a thrower operatively supported by the frame, devices for moving the thrower toward and away from the retorts, and motor mechanism for said devices to reciprocate the thrower to throw material into the retorts.

6. A machine of the character described, comprising a supporting frame, a thrower arranged to be moved toward and away from the charging ends of the retorts, mechanism for raising and lowering the thrower to positions to throw material into retorts at different heights, supports in said frame on which said thrower operates, a lever for moving said thrower toward and away from the charging ends of the retorts, and a lever for operating said thrower, and motor mechanism for operating said lever.

7. A machine of the character described, comprising a supporting frame located in front of the charging ends of retorts, a thrower operatively carried by said frame for movement toward and away from the charging ends of the retorts, mechanism for raising and lowering the thrower to positions to throw material into retorts at different heights, mechanism for moving said thrower away from the charging ends of the retorts to receive a load and toward the charging ends of the retorts to discharge the load, and means operated as an incident to movement of the thrower away from the retorts to deliver a load of material into the thrower.

8. A machine of the character described, comprising a laterally movable truck arranged for lateral movement across the charging ends of vertical series of retorts, a frame mounted on said truck for movement transversely thereof toward and away from the charging ends of the retorts, a vertically movable frame in the first-named frame, and mechanism operatively carried by said vertically movable frame for delivering material into the retorts.

9. A machine of the character described, comprising a supporting frame located adjacent to the charging ends of retorts, a vertically movable frame in the first-named frame, movable throwers carried by the vertically movable frame for throwing material into the retorts, a mechanism for moving the throwers rapidly toward the open ends of the retorts, and stopping such movement suddenly, the movement of the throwers toward the ends of the retorts being at sufficient momentum to throw the material from the throwers into the retorts when the throwers are suddenly stopped near the ends of the retorts, as aforesaid.

10. A machine of the character described, comprising a supporting frame located adjacent to the charging ends of retorts, movable throwers carried by the frame for throwing material into the retorts, operating mecha-

nism for moving the throwers rapidly toward the open ends of the retorts and stopping the movement of the throwers suddenly, adjacent to the open ends of the retorts, 5 movement of the throwers toward the retorts being at sufficient momentum to throw the material into the retorts when the throwers are suddenly stopped near the ends of the retorts as aforesaid, means for supporting 10 the throwers at different angles of inclination, and means for adjusting said throwers to serve retorts in different vertical positions.

11. A machine of the character described, 15 comprising a supporting frame located adjacent to the charging ends of retorts, movable throwers carried by the frame for throwing material into the retorts, operating mechanism for moving the throwers rapidly 20 toward the open ends of the retorts and stopping movement of the throwers suddenly adjacent to the open ends of the retorts, movement of the throwers toward the retorts being at sufficient momentum to 25 throw the material into the retorts when the throwers are suddenly stopped near the ends of the retorts, as aforesaid, means for adjusting said throwers to serve retorts in different vertical positions, and a track for 30 guiding the throwers to serve retorts at different angles of inclination.

12. A machine of the character described, 35 comprising a laterally movable frame located near the charging ends of retorts, a thrower carried by said frame for movement toward and away from the charging ends of the retorts, a chute for conducting material to load the thrower, a device for controlling the discharged material from the 40 chute into the thrower, and means for operating said device by the thrower during movement of the thrower away from the charging ends of the retorts.

13. A machine of the character described, 45 comprising a frame located near the charging ends of retorts, means for supporting the

frame in different vertical positions, a thrower, means for supporting the thrower at different angles of inclination, motor mechanism for operating the thrower to 50 throw material into the retorts, and an extendible and contractible chute in the frame for delivering material into the thrower, the extension and contraction of said chute being determined by the vertical 55 position of the thrower.

14. A machine of the character described, comprising a supporting frame, a thrower arranged to be moved toward and away 60 from the charging ends of the retorts, supports in said frame on which said thrower operates, means for adjusting said supports at different angles of inclination, operating mechanism for said thrower, and means for supporting said operating mechanism and said thrower in different vertical positions to 65 serve retorts in different vertical positions.

15. A machine of the character described, 70 comprising a laterally and vertically movable frame arranged for lateral and vertical movement near the charging ends of vertical series of retorts, a thrower in said frame, mechanism in said frame for operating said thrower to throw material into the retorts, means for supporting said thrower in different angles of inclination, and a motor for 75 operating said mechanism.

16. A machine of the character described, 80 comprising a laterally and vertically movable frame arranged for lateral and vertical movement near the charging ends of vertical series of retorts, mechanism in said frame for throwing material into the retorts, a motor for operating said mechanism, means for causing said mechanism to throw the material at different angles of inclination, and an extendible and contractible chute for delivering material to said thrower in any of the vertical or lateral positions of said 85 thrower.

JOHN EDWIN PEDERSEN.
